UNITED STATES PATENT OFFICE.

DEXTER M. SMALL, OF PROVIDENCE, RHODE ISLAND.

HEATING-DRUM.

SPECIFICATION forming part of Letters Patent No. 247,854, dated October 4, 1881.

Application filed March 1, 1880. (Model.)

To all whom it may concern:

Be it known that I, DEXTER M. SMALL, of Providence, in the State of Rhode Island, have invented a new and useful Improvement in 5 Heating-Drums, as follows, my object being increased heating-surface combined with convenience in form and structure, without increasing the size.

The accompanying drawing, which forms a 10 part of this specification, is a vertical section, showing one-half of the drum in an upright position.

In use the drum sits upon legs close to the back of the stove, being attached to the stove- 15 pipe by means of a pipe, B B', and consists of two upright casings, one within the other, of the same shape and height, but of different sizes, so there may be a space of an inch or more between them all around. This space is 20 closed at both top and bottom; but the inside casing is left open at both top and bottom, so the air may circulate up through freely. A partition, P P, is placed between the two casings at each end, extending from the top to 25 within an inch or more of the bottom, this space being left open for the hot air and smoke to pass through from one side of the drum to the other when there is no direct draft or when the direct draft is closed. Now, it having been 30 found necessary to construct the drum with a direct draft, I accomplish it in a cheap and convenient manner by making the inlet and outlet pipe of one piece and extending it through both sides of both the inner and outer casings, 35 placing a damper within it about midway between the sides of the inner casing, and perfor-

rating the pipe at c c and d d. When the damper is open of course there is a direct draft through the pipe B B', and when closed the circulation is as before, passing into the drum 40 through the holes c c and back into the pipe again through the holes d d. The damper could be placed in the pipe B B' outside the drum, in which case extra pipe, as indicated by the dotted lines, would be necessary, and 45 the pipe connecting the sides of the inner casing could be made separate from the inlet and outlet pipes, if desired.

I claim as my invention—

1. A heating-drum composed of two up- 50 right casings, one within the other, the inner one being open at both top and bottom, as described, together with the partitions P P, and the pipe B B' passing through both sides of both the outer and inner casings, having the 55 holes c and d or their equivalent therein, and also having a damper therein between the sides of the inner casing, all substantially as set forth.

2. A heating-drum composed of two upright casings, one within the other, the inner one 60 being open at both top and bottom, as described, together with the partitions P P and a pipe with a damper therein connecting the front and back compartments of the drum near the top, there being a suitable inlet and outlet 65 on opposite sides of the drum, all substantially as described.

DEXTER M. SMALL.
